UNITED STATES PATENT OFFICE.

ALDEN E. OSBORN, OF NEW YORK, N. Y.

INTERNAL-COMBUSTION ENGINE.

1,251,272.

Specification of Letters Patent. Patented Dec. 25, 1917.

Original application filed December 29, 1914, Serial No. 879,589. Divided and this application filed March 15, 1916. Serial No. 84,256.

To all whom it may concern:

Be it known that I, ALDEN E. OSBORN, a citizen of the United States of America, and a resident of New York, county and State of New York, have invented certain new and useful Improvements in Internal-Combustion Engines, for which I have filed an application for Letters Patent, Serial No. 879,589, on the 29th day of December, 1914, (patented January 16, 1917, No. 1,212,391) and of which this is a divisional application; furthermore, the following is a specification, reference being had to the accompanying drawings, forming a part thereof.

My invention relates to internal combustion engines and one of the objects is to provide a four-cycle engine of this type that shall be simple and compact in construction and efficient and powerful in operation.

A further object is to provide an improved valve construction which shall permit of a particularly advantageous arrangement of ports and which shall coöperate with the main piston in opening and closing the ports.

Other objects and advantages of my invention will be set forth hereinafter, and in order that my invention may be thoroughly understood I will now proceed to describe the same in the following specification and then point out the novel features thereof in appended claims.

According to my present invention the cylinder of the engine is constructed with two annular ports or sets of ports one of which is opened and closed by the operation of the engine piston and a surrounding sleeve valve.

Referring to the drawings:

Figure 1 is a sectional elevation of a sleeve valve engine which embodies the present invention.

Fig. 2 is a sectional plan view taken on the line 2-2 of Fig. 1 of the cylinder of the engine.

The engine here shown comprises a piston 30, which is surrounded by a sleeve valve 31 and is connected to a crank shaft 32 by a crank 33 and a connecting rod 34.

The sleeve valve has a lateral projection 35 at its outer end which is connected to a valve crank shaft 36 by a valve crank 37 and a connecting rod 38. The shafts 32 and 36 are connected by gears 39.

The cylinder of the engine comprises a main body portion 40, an upper body portion 41, and a pair of interposed hollow annular members 42 and 43 in which the exhaust port 44 and admission port 45 are respectively located.

The parts of the cylinder are fitted together and certain of them are provided with annular notches so as to provide pockets or grooves 46, 47 and 48 in which packing rings 46^A, 47^A and 48^A are located.

The arrangement of parts is such that the packing ring 47^A is interposed between the members 42 and 43 and between the exhaust and inlet passages, the packing ring 46^A is between the annular member 42 and the upper body portion 41 of the cylinder, and the packing ring 48^A is between the annular member 43 and the main body of the cylinder.

As explained in detail hereinafter, the exhaust ports 44 and the annular passage with which it communicates, are uncovered during the exhaust stroke on account of the displacement of the sleeve valve; on the other hand, the admission ports and the passage with which it communicates are opened into the cylinder through a plurality of radial openings 51 in the valve sleeve, the piston being displaced at the proper time to uncover these openings. The two parts of the cylinder and the interposed members 42 and 43 are held together by bolts or tie rods 50.

The operation of this engine is as follows: Assuming that the parts occupy the positions in which they are shown in the drawings,—that a compressed charge has just been fired and that the valve sleeve is reciprocating at one-half the speed of the piston; the piston 10 is moved outwardly through its working stroke and the sleeve valve will advance in the same time, a distance corresponding to a 90 degree movement of the crank 37. When the piston moves through about one-half of its working stroke, it is below the annular passage which communicates with the admission port; but this passage is previously covered because the sleeve valve has advanced a distance corresponding to about a 45 degree movement of the crank 37.

The next stroke of the piston is the exhaust stroke and during this stroke the piston moves a distance corresponding to another quarter turn of the valve crank. The

arrangement of parts is such that the exhaust port is open at the beginning of the stroke, the burnt gases are forced out, and the exhaust port again covered. During the suction stroke of the piston which is next, the valve crank advances another quarter turn and the sleeve valve occupies a position approximately as shown in Fig. 1 but is moving in the opposite direction toward the inner end of its stroke.

The openings 51 in the sleeve valve thus register with the annular passage which communicates with the admission port 45, and fuel will pass into the cylinder, there being, of course, a partial vacuum formed in the combustion chamber during the first part of the suction stroke until the piston has advanced sufficiently to uncover the openings 51. The fuel is supplied in the usual way through the remainder of the stroke.

During the beginning of the compression stroke, the admission port 45 is opened but is soon closed by the sleeve valve which is moving over its inner center; later in this stroke the piston covers the openings 51 and consequently the fuel is prevented from being forced out into the carburetor, when the sleeve valve moves to such a position that the openings 51 again register with the admission port.

The structure illustrated may be modified in various particulars without departing from the spirit and scope of my invention, and I intend that only such limitations be imposed as are indicated in the appended claims.

What I claim is:

1. An internal combustion engine comprising a cylinder having a pair of independent sections and interposed hollow an-

nular members provided respectively with admission and exhaust ports, a sleeve valve within the cylinder, and a piston within the sleeve valve.

2. An internal combustion engine comprising a cylinder having a pair of independent sections and interposed hollow annular members provided respectively with admission and exhaust ports, a sleeve valve within the cylinder having a plurality of openings adapted to open communication between the admission port and the cylinder, and a piston within the valve cylinder, said sleeve valve being adapted to uncover the exhaust port at the outer end of its stroke.

3. An internal combustion engine comprising a cylinder having a pair of independent sections and interposed hollow annular members provided respectively with admission and exhaust ports, a sleeve valve within the cylinder having a plurality of openings adapted to open communication between the admission port and the cylinder, and a piston within the valve cylinder, said sleeve valve being adapted to cover the admission port at the inner end of its stroke and thereby prevent loss of compression before the admission port is covered by the piston.

4. An internal combustion engine comprising a cylinder having a pair of independent sections and an interposed hollow annular member provided with a port, a sleeve valve within the cylinder, and a piston within the sleeve valve.

In witness whereof, I have hereunto set my hand this 8th day of March, 1916.

ALDEN E. OSBORN.
